UNITED STATES PATENT OFFICE.

THURE E. DAHL, OF NEW YORK, N. Y.

DESIGN FOR AN ARM FOR ELECTRIC FIXTURES.

• 61,062.

Specification for Design. Patented June 13, 1922.

Application filed May 31, 1921. Serial No. 473,929. Term of patent 3½ years.

To all whom it may concern:

Be it known that I, THURE E. DAHL, a subject of the King of Sweden, residing at New York, in the county of New York and State of New York, in the United States of America, have invented a new, original, and ornamental Design for an Arm for Electric Fixtures, of which the following is a

specification, reference being had to the accompanying drawing, forming part thereof. The figure is a side view of an arm for electric fixture, showing my new design.

I claim:

The ornamental design for an arm for electric fixtures, as shown.

THURE E. DAHL.
